UNITED STATES PATENT OFFICE.

GEORGE A. MILLER, OF TAMAROA, ILLINOIS.

RAILROAD-CROSSING SIGNAL.

1,370,831.

Specification of Letters Patent.

Patented Mar. 8, 1921.

Application filed June 3, 1920. Serial No. 386,335.

To all whom it may concern:

Be it known that I, GEORGE A. MILLER, a citizen of the United States, residing at Tamara, in the county of Perry and State 5 of Illinois, have invented new and useful Improvements in Railroad-Crossing Signals, of which the following is a specification.

This invention relates to signal apparatus 10 designed for installation at railway crossings to indicate to pedestrians or drivers of vehicles the approach of trains, and the invention has for its object to provide a novel and improved signal apparatus of this kind 15 which is entirely automatic in operation, the control being effected by the train traveling toward the crossing.

The invention also has for its object to 20 provide the signal apparatus with an indicator for communicating to the engineer or motorman the fact whether or not the apparatus is properly functioning.

With the objects stated in view, the invention consists in a combination and arrangement of parts to be hereinafter described and claimed, and in order that the same may be better understood, reference is had to the accompanying drawings forming a part of this specification.

30 In the drawings,

Figure 1 is a plan view of the apparatus;

Fig. 2 is a cross section on the line 2—2 of Fig. 1;

Fig. 3 is an enlarged sectional detail on 35 the line 3—3 of Fig. 1;

Fig. 4 is a view similar to Fig. 3 with the parts shown in another position;

Fig. 5 is an elevation of the apparatus in display position;

40 Fig. 6 is a vertical section on the line 6—6 of Fig. 2, with the parts shown in non-display position, and

Fig. 7 is an enlarged elevation of an 45 electro-magnet and certain parts associated therewith.

Referring specifically to the drawings, 50 denotes the rails of a railway track mounted on stringers or ties 11 as usual. At the crossing or any other point along the track where protection is to be afforded is erected a hollow post 12 rising to a suitable height and housing a signal arm or blade 13, the latter being carried by and extending radially from a shaft 14 journaled in opposite

walls of the housing. When in a non-display position, the signal arm 13 occupies a pendent position in the post 12, and it is adapted to be swung to extend horizontally from the post, as shown in Fig. 5, this being the display position. The arm 13 55 swings upwardly to display position, and it passes into and out of the post 12 through a slot 15 in the side wall thereof.

Alongside the post 12, one of the ties 11 carries bearings 16 in which is journaled a 60 horizontally positioned rock-shaft 17 having a crank arm 18 which is connected by a link or rod 19 to the signal arm 13 whereby, when said shaft is rocked in one direction, the arm is swung upwardly and outwardly 65 to display position, whereas a movement of the shaft in the opposite direction allows the arm to swing back into the post 12 to non-display position.

From the shaft 17 also extends a lever 70 arm 20 to which is connected one end of a strong coiled spring 21 having its other end anchored to one of the ties 11.

Opposite the free end of the lever arm 20 is positioned the pivoted armature 22 of an 75 electro-magnet 23 supported by one of the ties 11. The armature 22 has teeth 24 with any one of which the extremity of the lever arm 20 is adapted to be engaged to hold it 80 down against the tension of the spring 20, 85 the armature therefore acting as a latch device for the lever arm.

The electro-magnet 23 is interposed in an open track circuit which is closed when a train enters the track section. This is a well 90 known circuit arrangement and hence it need not be illustrated, nor further described, except that it is to be understood that the electro-magnet is energized when the circuit is closed by the approaching 95 train, and that this action takes place some distance from the site of the signal apparatus, so that the signal arm 13 may be swung to display position a suitable period of time before the train reaches the crossing. The track section in which the circuit is included also terminates some distance from the crossing, so that the circuit is broken by the time the train reaches the crossing. A momentary closing of the circuit 100 is all that is necessary to energize the electro-magnet, after which the circuit may be broken without affecting the subsequent 105

operations of restoring the arm 13 to non-display position after the train passes the crossing.

When an approaching train closes the track circuit, the electro-magnet 23 is energized, whereupon the armature 22 is attracted to release the lever arm 20. The spring 21 now functions to swing the lever arm and rock the shaft 17, whereby, through the connections 18 and 19, the signal arm 13 is swung to display position, and is so held by the spring. When the train passes the crossing, the wheels passing over the elevated lever arm 20 will depress the same, thereby rocking the shaft 17 in a direction to allow the signal arm 13 to swing back into the post 12 to non-display position. As the lever arm 20 is forced down it catches on the teeth of the armature 22 and is thus locked in lowered position against the tension of the spring 21, and the parts are now back to their normal position for the next actuation. It will be understood that the lever arm 20 seats closely alongside one of the rails 10 so that the car wheels may come in contact with said arm when they pass over the same.

The connection between the shaft 17 and the lever arm 20 is made by a radially projecting pin 25 carried by said shaft and extending in a slot 26 in the hub of the lever. Thus, when the arm 20 is pressed down by the car wheel, and the end of the slot moves away from the pin, the signal arm 13 can drop by gravity to non-display position.

The post 12 also carries an electric bell 27 and a lamp 28 obtaining current from a suitable source shown diagrammatically at 30. The circuit of the bell and the lamp 40 is controlled by a switch composed of a stationary contact 31 and a switch tongue 32 normally spaced therefrom and adapted to come into contact therewith when the arm 13 is swung to display position, the tongue 45 32 being in the path of the crank arm 18. When the arm 13 moves to non-display position and the crank arm 18 leaves the switch tongue 32, the lamp and bell circuit is broken. It will therefore be seen that the 50 control of the signal lamp and bell is entirely automatic.

In order to indicate to the engineer or motorman of the approaching train the condition of the signal apparatus, an auxiliary 55 signal arm 34 is provided. This signal arm is fastened to the shaft 14 of the arm 13 and it extends lengthwise therefrom and horizontally from the side of the post 12 facing the track. The arm 34 is so connected to

the shaft 14 that it is horizontal as shown in Fig. 6 when the arm 13 is down in the non-display position, and when the latter is in display position, the arm 34 is vertical as shown in Figs. 1, 2 and 5, the side of the latter being now plainly visible. It will therefore be seen that the engineer or motorman of the approaching train may observe whether the crossing signal apparatus is properly functioning, so that he may stop the train or slow up and proceed with caution if the arm 34 indicates that the arm 13 has not been swung to display position.

I claim:

1. A railway crossing signal comprising a signal arm, a pivotal support for said arm, a rock shaft having an operative connection with the signal arm, a lever arm operatively connected to the rock shaft for turning the same in a direction to swing the signal arm to display position, said connection being a loose one to permit the shaft to turn in a direction to allow the signal arm to swing to non-display position, a spring connected to the lever arm for operating the same to turn the rock shaft in a direction to place the signal arm in display position, said lever arm being positioned for train actuation to effect the return of the signal arm to non-display position, a latch for locking the lever arm when the signal arm is in non-display position, an electro-magnet controlling the latch, and a train controlled energizing circuit for the electromagnet.

2. A railway crossing signal comprising a signal arm, a pivotal support for said arm, a rock shaft having an operative connection with the signal arm, a lever arm operatively connected to the rock shaft for turning the same in a direction to swing the signal arm to display position, said connection being a loose one to permit the shaft to turn in a direction to allow the signal arm to swing to non-display position, a spring connected to the lever arm for operating the same to turn the rock shaft in a direction to place the signal arm in display position, said lever arm being positioned for train actuation to effect the return of the signal arm to non-display position, a latch for locking the lever arm when the signal arm is in non-display position, an electro-magnet controlling the latch, a train controlled energizing circuit for the electro-magnet, and an auxiliary signal arm movable with the aforesaid signal arm and extending in a different direction.

In testimony whereof I affix my signature.
GEORGE A. MILLER.
